HYDRAULIC CLEANER FOR DRAINS AND
THE LIKE

Joseph Leyden, Marshall, Mich.

Application March 25, 1941, Serial No. 385,201

6 Claims. (Cl. 4—256)

The present invention relates broadly to hydraulic devices, and in its specific phases to plunger type devices for breaking up obstructions in drain pipes and flushing same therethrough.

The ordinary procedure used in the past for opening clogged drain pipes has been to either take the pipe apart and clean it, run a hose or flexible cable through same, or use a plunger of the type commonly referred to as the "plumber's friend." Complex devices using pistons or the like which slidably fit the interior of the end of the clogged pipe, or a cylinder attached thereto, have been proposed, but apparently have not been a commercial success. The complexities of such apparatus and the shortcomings of the devices of the ordinary plunger type, as well as substitutes for same, showed the need of an improved drain opening device and led to the development of the present invention.

Accordingly among the objects of the present invention is the provision of a simplified, easily constructed, and readily operated apparatus adapted to break up accumulations in drain pipes and force same out of the pipe to the sewer main, or other connection thereto.

Another object is to provide a drain opening apparatus which not only employs hydraulic pressure equal to the conventional water system pressure, but also makes possible the increasing of such pressure by pulsating action.

A further object is to provide a simplified device wherein water is supplied to the clogged drain under pulsating and rotary flow, thus increasing the outward scouring pressure of the flowing water due to the centrifugal action involved.

Still further objects and advantages of the present invention will appear as the description proceeds.

To the accomplishment of the foregoing and related ends, the invention, then, consists of the means hereinafter fully described and particularly pointed out in the claims, the annexed drawing and the following description setting forth in detail certain means for carrying out the invention, such disclosed means illustrating, however, but one of various ways in which the principle of the invention may be used.

In said annexed drawing:

Figure 1 shows a partially sectioned vertical view illustrating a preferred form of the device of the present invention in applied position.

Figure 2 shows an adapter forming a remov-

able portion of the present device usable for connecting threaded faucets thereto.

While the device which embodies the present invention is applicable in general for use in cleaning or forcing out pipe line obstructions, it is particularly adapted for use in forcing obstructions from drain pipes leading from a sink, water closet bowl, or other devices of this general class commonly installed in buildings.

Referring more particularly to Figure 1 of the drawing, the device comprises a plunger cup 1, preferably having relatively heavy but flexible and resilient walls formed from rubber or suitable synthetic rubber. The lower edge of the cup 1 is normally provided with a flange 2 to facilitate the stabilization of the bell-shaped plunger cup under conditions of operation, and also to improve the sealing action thereof. The upper end or apex of cup 1 is provided with a hollow extending neck 3 into which hollow tube 4 extends and is fastened in place with a suitable clamp 5. Passageway 6 connects the interior of plunger cup 1 to the interior of the end of hollow tube 4 for fluid flow therebetween. Joined to the upper end of hollow tube 4 by means of threads or the like is a short nipple 7. The lower end 8 of this nipple is preferably beveled to form a sealing seat for valve member 9 which may be in the form of a ball bearing. Suitable means may be used for allowing limited movement of the valve member in the end of hollow tube 4 and one convenient means for accomplishing this purpose is a pin 10 which preferably extends completely through hollow tube 4 for purposes of stability. A flexible tube 11 which may be in the form of rubber hose or the like, is connected to the free end of nipple 7 by means of clamp 12 or the equivalent. The other end of hose 11 is fastened to a coupling member 13 by means of a hose clamp 14. For simplicity of construction and operation, a conventional pressure gripping type of coupling member is used. Such a coupling member frictionally grips the part to which it is to be attached, and the moment that fluid pressure is exerted inside of the coupling, it increases its frictional grip on such member. Where the device is to be connected to a conventional threaded faucet 15, the adapter 16 (Figure 2) is utilized as part of the assembly. In this case the body 17 of the adapter 16 is inserted into the open end of coupling member 13, and the internally threaded cap 18 is screwed onto the threaded spout 19 of faucet 15. Where the faucet has a plain unthreaded spout, adapter

16 is removed from coupling member 13 and the latter connected directly to the faucet spout.

The apparatus is shown mounted in place in a conventional sink 20 with plunger cup 1 over removable strainer 21 which covers the inlet end of drain pipe 22. In order to produce a rotating flow of water within the plunger cup 1 and drain pipe 22 under conditions of use, a spiral member 23 is placed in hollow tube 4 and anchored thereto, for instance, by means of rivets 24 which preferably extend completely through hollow tube 4 so as to absorb the torque exerted by the spirally flowing fluid. The upper end of spiral member 23 may also be used as a stop for valve member 9 in the place of pin 10. This spiral flow of the fluid delivered from hollow tube 4 causes same to flow in like direction after reaching the interior of plunger cup 1, and to continue such rotary movement under flow into drain pipe 22. In order to facilitate this curved path flow, strainer 21 is preferably removed at the start of the drain cleaning operation. This rotary fluid movement presents the advantages of outward pressure due to centrifugal action, thus not only increasing the scouring and cleaning action on the drain pipe, but also providing what may be termed a live boring action which again helps in opening and flushing the clogged system.

A conventional size of apparatus of the type illustrated and suitable for use in opening pipes, such as sink drains, involves the use of a five-inch diameter heavy rubber plunger cup mounted on a piece of $\frac{1}{2}$ inch brass or galvanized pipe approximately fifteen inches long, the upper end of which has a $\frac{3}{8}$ inch brass nipple threaded thereinto. A suitable length piece of standard $\frac{1}{2}$ inch hose is used to join the upper end of this nipple to the coupling member 13 which in turn is adapted to be connected to a conventional faucet either directly or by means of an adapter 16 where the faucet spout 19 is threaded for attaching a hose coupling. The lower end of nipple 1 is preferably beveled at a suitable angle, for instance 45 degrees, to form a tight seal with valve member 9 which may be in the form of a substantially rust-proof ball bearing. A $\frac{7}{16}$ inch diameter stainless steel ball bearing is well suited for use with pipe of the size noted. Pin 10 acts as a stop for valve member 9 and in preferred construction allows same to move endwise of hollow tube 4 a distance approximately in the range of $\frac{1}{16}$ inch to $\frac{1}{8}$ inch. Under plunging action the back flow of fluid through hollow pipe 4 carries valve member 9 up against the lower end 8 of nipple 1 to form a tight seal therewith. The spiral member 23 is preferably formed from a rust-proof material such as heavy strip brass or bronze which has been twisted or otherwise formed as shown. The number of spiral turns in this strip for a given length thereof determines to a large extent the rotary motion of the fluid as it passes into plunger cup 1 and flows therethrough into drain pipe 22. Suitable fastening means such as rivets 24 preferably of $\frac{1}{8}$ to $\frac{1}{16}$ inch diameter are used to hold spiral member 23 in place. While one rivet may be used for this purpose, it is usually preferable to use at least two as shown since such procedure aids in stabilizing spiral member 23 against twisting motion.

In operating the device for opening a sink drain or the like, strainer 21 is preferably removed from the open end of clogged drain pipe 22 and after coupling member 13 is attached to spout

19 of faucet 15, plunger cup 1 is placed over the entrance to drain pipe 22 and in contact with the bottom of sink 20. By turning handle 25 of faucet 15 to direct water through the device, such water after filling the tubing and plunger cup 1, while the latter is held in place, will exert static pressure on drain pipe 22. Then by grasping hollow pipe 4 and moving same up and down in plunger fashion, a series of high pressure pulsations of water moving under rotary flow will be impressed into the open end of drain pipe 22 thus producing dynamic fluid pressures in surges exceeding the normal static water pressure at the faucet. This action is highly effective in quickly opening drains which are plugged tighter than a conventional hand plunger will open, and at the same time more effectively opens and flushes drains where an ordinary hand plunger is commonly used.

Other modes of applying the principle of my invention may be employed instead of the one explained, change being made as regards the article and combination herein disclosed, provided the means stated by any of the following claims or the equivalent of such stated means be employed.

I therefore particularly point out and distinctly claim as my invention:

1. A hydraulic drain cleaner, which comprises a plunger cup, means for connecting said plunger cup to a suitable source of fluid supply, a check valve, said check valve being adapted to substantially prevent back flow of fluid through said connecting means toward said source of supply, and means to cause fluid flowing through said connecting means into said plunger cup to assume a curved path in the latter.

2. A hydraulic drain cleaner, which comprises a plunger cup, means for connecting said plunger cup to a suitable source of fluid supply, said connecting means and cup having a continuous fluid passageway therethrough, means to cause fluid flowing through said connecting means into said plunger cup to assume a curved path in the latter, and means to substantially prevent fluid flow from said plunger cup back through said connecting means.

3. A hydraulic drain cleaner, which comprises a relatively heavy walled, flexible, and resilient plunger cup having a hollow extending neck at the apex thereof, a hollow tubular member acting as a fluid conduit and operating handle, means for connecting the hollow extending neck of said plunger cup to one end of said tubular member in manner forming a substantially fluid tight joint therewith, means in said tubular member to cause fluid flowing therethrough to assume a spiral path, and flexible means to connect the other end of said tubular member to a suitable source of fluid supply for flow through said tubular member into said plunger cup.

4. A hydraulic drain cleaner, which comprises a plunger cup having a hollow extending neck at the apex thereof, a hollow tubular member, means for connecting the hollow extending neck of said plunger cup to one end of said tubular member in manner forming a substantially fluid tight joint therewith, means in said tubular member to cause fluid flowing therethrough to assume a spiral path, a hollow nipple fitting into the other end of said tubular member, a valve member in said tubular member for substantially preventing fluid flow through said tubular member into said nipple, and a flexible means to connect the other end of said nipple to a suitable

source of fluid supply for flow through said tubular member into said plunger cup.

5. A hydraulic drain cleaner, which comprises a plunger cup, a rigid hollow tubular member connected at one end to the apex of said plunger cup, a hollow nipple fitting the other end of said tubular member, a ball bearing within said tubular member and adapted to abut the end of said nipple for sealing purposes while permitting flow through said tubular member into said plunger cup, means substantially restricting said ball bearing to limited movement lengthwise of said tubular member, said limited movement of the ball bearing in said tubular member facilitating said fluid flow as well as quick sealing on reverse flow, and suitable means to connect the other end of said nipple to a suitable source of fluid supply for flow through said tubular member into said plunger cup.

6. A hydraulic drain cleaner, which consists of a resilient rubber plunger cup having a hol-

low extending neck at the apex thereof, a rigid hollow tubular member, means for fastening the hollow extending neck of said plunger cup to one end of said tubular member, a spiral member mounted in fixed position in said tubular member to cause rotary flow of fluid delivered through said tubular member into said plunger cup, a hollow nipple fitting into the other end of said tubular member, the end of said nipple within said tubular member being internally beveled to form a valve seat, a ball bearing within said tubular member, said ball bearing being adapted to co-operate with said seat for sealing purposes while permitting flow through said tubular member into said plunger cup, a suitable rubber hose fixedly joined to the other end of said nipple, and a coupling member fixedly joined to the opposite end of said hose for connecting same to a suitable source of fluid supply.
